(57) **CLAIM**

We claim the ornamental design for a pump, as shown and
described.

DESCRIPTION

FIG. 1 is a perspective view of a pump with a pendant removed.
FIG. 2 is a right side view of the pump as shown in FIG. 1.
FIG. 3 is a left side view of the pump as shown in FIG. 1.
FIG. 4 is a front view of the pump as shown in FIG. 1.
FIG. 5 is a rear view of the pump as shown in FIG. 1; and,
FIG. 6 is a top view of the pump as shown in FIG. 1.
Any line in a drawing may provide a boundary line of a
claimed design element. A boundary line of a claimed design
element may be defined in an area between lines in a
drawing. An element or a subset of any combination of
elements in a drawing may form a claimed design. Any
portion of the pump shown in broken lines is included for the
purpose of illustrating environment and forms no part of the
claimed design. In FIGS. 1-6, the broken lines illustrate
portions of the pump that form no part of the claimed design.
